UNITED STATES PATENT OFFICE.

WILL CAMERON McCARTNEY, OF CAMBRIDGE, OHIO.

DESIGN FOR A TRAY FOR CONDIMENTS SETS.

Application filed October 25, 1927. Serial No. 23,874. Term of patent 3½ years.

To all whom it may concern:

Be it known that I, WILL CAMERON McCARTNEY, a citizen of the United States, residing at Cambridge, in the county of Guernsey and State of Ohio, have invented a new, original, and ornamental Design for a Tray for Condiment Sets, of which the following is a specification, reference being had to the accompanying drawing, forming part thereof.

Fig. 1 is a top plan view of a tray for condiment sets, showing my new design, and

Fig. 2 is an end elevation.

I claim—

The ornamental design for a tray for condiment sets as shown.

WILL CAMERON McCARTNEY.
